LADDER

Peter Pirsch, Kenosha, Wis., assignor to Peter Pirsch and Sons Co., Kenosha, Wis., a firm composed of Peter Pirsch, W. R. Pirsch, and Ceila Pirsch Even

Application May 17, 1937, Serial No. 143,024

3 Claims. (Cl. 223—58)

This invention relates to improvements in ladders.

In the manufacture of ladders, the securing of the ends of the rungs in position has heretofore presented a problem. These rungs must be rigidly connected to the side rails in order to properly brace the ladder structure and also to hold the rungs themselves against loosening and turning movement. Ladders as constructed to-day may be formed in a variety of ways: rungs of aluminum or other metal may be used in conjunction with side rails of wood; the ladder may utilize metal for both the side rails and the rungs; or the ladder may be of a standard type employing wood for both the side rails and rungs. Where metal rungs are employed, the problem of securing the ends of the rungs in position is increasingly difficult, and welding has heretofore been resorted to to make a firm connection.

It is one of the objects of the present invention to provide a simple means for anchoring the ends of the rungs in position and for spacing and strengthening the elongated members forming the side rails, which means is adapted for use in connection with any of the above types of ladder constructions, and which means is particularly well adapted for use in connection with metal rungs.

It is a more specific object of this invention to provide an improved ladder construction comprising side rails each formed of a pair of spaced elongated members, rungs positionable between the side rails, and means forming spacers or truss blocks positionable between the elongated members forming the side rails and specially constructed to receive and firmly anchor the ends of the rungs.

A further object of the invention is to provide a ladder construction as above described where-40 in the spacer blocks are of metal and of spider form presenting relatively long bearing sleeves for the ends of the rungs, which sleeves may be broached to proper form to snugly receive the ends of grooved metal rungs or the ends of wooden rungs where these are employed.

Other objects of the invention are to provide a ladder construction embodying a spacer block wherein the latter is of open form to permit riveting through exposed exterior portions of the bearing sleeve and also to provide openings for reception of the hand when the ladder is being used; to provide a ladder construction adapted for use in connection with either a lap type of extension ladder or a lapless type; to provide a ladder which permits the use of aluminum

throughout, if desired, thereby providing a construction of minimum weight; to provide a ladder in which both the side rails and rungs are reinforced and strengthened by the improved spacer and truss blocks; to provide a construction which eliminates the necessity of welding the ends of metal rungs in position when metal is used for the rungs; and to provide a construction which is relatively simple and inexpensive to manufacture.

With the above and other objects in view, the invention consists of the improved ladder and all its parts and combinations as set forth in the claims and all equivalents thereof.

In the accompanying drawing in which the same reference numerals designate the same parts in all of the views:

Fig. 1 is a perspective view of a fragment of a ladder;

Fig. 2 is an enlarged fragmentary view looking at the inner side of a side rail assembly, the rung being shown in section, and other parts being broken away and shown in section;

Fig. 3 is a perspective view of one of the spacer members alone;

Fig. 4 is a fragmentary perspective view showing a modified construction wherein the side rails are formed of spaced channel members of aluminum or other metal;

Fig. 5 is a sectional view through one of the rungs of the modification looking at the side rail and spacer assembly; and

Fig. 6 is a sectional view taken on line 6—6 of Fig. 5.

Referring more particularly to Figs. 1, 2 and 3 of the drawing, the ladder shown therein comprises spaced side rail assemblies 8 and 9, each comprising a pair of elongated members 10 and 10'. Secured at intervals between the elongated members 10 and 10' are the improved spacer members designated generally by the numeral 11. These spacer members are preferably formed of aluminum or other metal and are of spider form. In the preferred embodiment each spacer includes a strip of metal 12 which is secured to the elongated member 10' by bolts 13, said strip having a sleeve portion 14 projecting therefrom as shown. Extending angularly from the sleeve are arms 15 which have their outer ends flanged as at 16 whereby the arms may be secured by the bolts 17 to the elongated member 10.

In the form of invention shown in Fig. 1, the elongated members 10 and 10' are formed of wood. This is preferred in many cases because of the fact that wood is not a conductor of elec-

tricity, and there is therefore no danger when the ladder touches a live wire. Elongated members of wood are also preferred by many because of the fact that they are not as cold on the hand in the winter time. Frequently, however, where maximum lightness is desired, the elongated members comprising the side rails are formed of light weight metal such as aluminum, and the improved spacer block is well adapted for use in conjunction with side rail assemblies of this type. By referring to Fig. 4, it will be seen that the elongated members forming the side rails 17 and 18 are of channeled metal with the open sides of the channel facing each other. The spacer members may then be fitted between the flanges 19 and 20 of the channels as shown and filler strips 25 may be employed if desired. Various other forms of side rails may be employed in connection with the improved spacer members, such as side rails formed of I-beams.

The use of rungs formed of aluminum or other light weight metal is highly desirable due to the fact that said rungs resist breakage and are light in weight, and the present invention lends itself well to use in connection with rungs of this type. These aluminum rungs 21 are usually formed with longitudinal ribs 22 to prevent slippage of the foot. Accordingly in securing the ends of metal rungs in position the sleeve portions 14 of the spacers are suitably broached to provide grooves 23 for cooperation with the ribs of the rungs. The ends of the rungs are then inserted into the sleeves 14 with a driving fit, and they are thus tightly secured in position. The sleeves, it is to be noted, are sufficiently long to provide a relatively long bearing surface for the ends of the rungs. In addition the cooperating ribs 22 and grooves 23 prevent turning movement of the rungs in the sleeves. In order to further secure the rungs in position and against turning movement, a rivet 24 may be inserted through an exposed exterior portion of the rung, the rung being tubular in form. Due to the fact that the spider-like form of the spacers exposes exterior portions of the sleeve 14, this riveting is a simple matter. It will therefore be seen that a very secure connection can be made with the ends of the rungs without in any way resorting to welding.

Where wooden rungs are employed, it is preferred to also broach the sleeves 14 to provide the grooves 23 separated by the ribs between the grooves. The ends of the wooden rungs are then driven into the sleeves with the ribs between the grooves cutting into the wood. Thus the wooden rungs may also be firmly secured in position and against turning movement. It is also possible to drive a nail or other securing means into the wooden rung in place of the rivet 24 used with the metal rung construction.

From the above it may be seen that the improved construction is well adapted for use in connection with side rails of either wood or metal or in connection with rungs of either wood or

metal. It is further apparent that the open structure of the spacer simplifies the insertion of securing members such as the rivet 24. The spider construction of the spacers also serves as a truss to strengthen and brace the entire ladder construction. In using a ladder it is undesirable to have the elongated members forming the side rails closed for any appreciable length. The spider-like spacer blocks are therefore particularly desirable because the hand can be inserted around the elongated member 10 and between the spider arms 15. In addition, the spacer blocks of the present invention are formed of metal and therefore there is no trouble in connection with shrinkage such as was heretofore encountered when wooden spacer blocks were employed. With the wooden blocks, not only the rungs became loose, but also the bolts which held the wood spacers to the side rails.

Although only a few forms of the invention have been shown and described, it is obvious that various changes and modifications may be made without departing from the spirit of the invention, and all of such changes are contemplated as may come within the scope of the claims.

What I claim is:

1. A ladder comprising side rails each including a pair of spaced elongated members, spacers secured at intervals between said spaced elongated members of each side rail, each spacer comprising a strip of material secured to one of said elongated members of a side rail, a bearing sleeve projecting from said strip, arms projecting angularly from said sleeve and secured to said other elongated side rail member, and rungs having end portions received in said sleeves.

2. A ladder comprising side rails each including a pair of spaced elongated members, spacers secured at intervals between the spaced elongated members of each side rail, each spacer including a metal bearing sleeve, means for connecting said sleeve to one of the spaced members in a position relatively close to said member, and spaced arms extending at an oblique angle away from each other connecting the sleeve to the other spaced member to provide a relatively large hand opening between said arms, and rungs having end portions received in said sleeves.

3. A ladder comprising side rails each forming a pair of spaced elongated metal members having channel portions opening toward each other, spacers secured at intervals in said channel portions and connecting the elongated members together, each spacer including a metal bearing sleeve of a minimum length substantially equal to the width of the channels, and arms connecting said sleeves to the channels, said arms being of a width to fit between the flanges of the channels and said width of the arms extending in the same direction as the length of the sleeve, said sleeves and spacers being substantially confined within the channels, and rungs having end portions received in said sleeves.

PETER PIRSCH.
